UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 27,236, dated June 22, 1897.

Application filed May 6, 1897. Serial No. 635,426. Term of patent 7 years.

To all whom it may concern:

Be it known that I, WILLIAM C. CODMAN, a subject of Her Majesty the Queen of Great Britain, residing at Providence, in the county 5 of Providence and State of Rhode Island, have invented and produced a new and original Design for the Handles of Spoons, Forks, and Similar Articles, of which the following is a specification, reference being had to the accompanying drawings, forming part thereof.

Figure 1 is a view of the obverse side of a handle, showing my design. Fig. 2 is a view of the reverse side of the same.

The leading feature of my design consists 15 in the raised marginal ornamentation of the slightly-tapering stem of the handle and of the oval forming the upper end of the handle.

In the drawings, A designates the bowl of a spoon or other article to which the handle 20 is attached, B the stem of the handle, and C the blade forming the upper part of the handle. The stem B, which slightly contracts midway its length, is of nearly uniform width.

The margins of the stem are ornamented by the raised beads *d d*, terminating at the lower 25 end in the foliated ornaments *e* and at their upper ends in the inwardly-curving scrolls *f*. From the scrolls *f* extend the slightly-outward curved abacus leaves *g*, on which the narrow end of the oval *h* is supported. The 30 oval is inclosed by raised beads terminating in scrolls and is surmounted by the raised ornament. To the eye the handle presents the conventional appearance of a small Greek mirror supported on a stem.

Having thus described my invention, what I claim as new, and desire to secure by Letters Patent, is—

The design for the handle of a spoon, fork, or similar article herein shown and described. 40

In witness whereof I have hereunto set my hand.

WILLIAM C. CODMAN.
